United States Patent Office

Des. 206,962
Patented Feb. 14, 1967

206,962

BOTTLE

Richard L. Weckman, Perrysburg, Ohio, assignor to Owens-Illinois, Inc., Toledo, Ohio, a corporation of Ohio

Filed May 23, 1966, Ser. No. 2,395

Term of patent 14 years

(Cl. D58—8)

FIG. 1

The back is a mirror image of the front.

The characteristic features of this design reside in the configuration shown in full lines on the drawing.

I claim:

The ornamental design for a bottle, substantially as shown and described.
